Patented Oct. 24, 1967

209,034

BASE FOR A DRINKING FOUNTAIN

Donald D. Johnson, Bountiful, Utah, assignor to Buehner
Research and Development, Salt Lake City, Utah, a
limited partnership

Filed Apr. 25, 1966, Ser. No. 2,005

Term of patent 14 years

(Cl. D91—4)

FIG. 1

Des. 209,034

PAGE 2

FIG. 2

FIG. 3

FIG. 1 is a front view of a drinking fountain embodying my design;

FIG. 2 is a side view, and
FIG. 3, a top plan view.

I claim:

The ornamental design for a base for a drinking fountain, substantially as shown.
